Primary Examiner — Eric Goodman*Assistant Examiner* — Ryan Harvey(74) *Attorney, Agent, or Firm* — McNair Law Firm, P.A.;
Douglas W. Kim(57) **CLAIM**

The ornamental design for a Wanyu pedal design, as shown and described.

DESCRIPTION

FIG. 1 is a top perspective view of the Wanyu pedal design;
 FIG. 2 is a top view thereof;
 FIG. 3 is a bottom view thereof;
 FIG. 4 is a right side view thereof;
 FIG. 5 is a left side view thereof;
 FIG. 6 is a rear view thereof; and,
 FIG. 7 is front view thereof.

The broken lines illustrate portions of the article that form no part of the claimed design.
